UNITED STATES PATENT OFFICE.

ABRAHAM TAYLOR, OF MANCHESTER, ENGLAND.

WASHING PLUNGER, DOLLY, AND THE LIKE.

Application filed February 16, 1921. Serial No. 445,392.

To all whom it may concern:

Be it known that I, ABRAHAM TAYLOR, a subject of the King of Great Britain and Ireland, and a resident of Swinton, Manchester, in the county of Lancaster, England, have invented certain new and useful Improvements in Washing Plungers, Dollies, and the like, of which the following is a specification.

10 This invention has reference to washing plungers, dollies and the like, and it has for its object to provide improvements in such devices whereby they are of considerably stronger construction, more convenient in 15 use, and less liable to fracture than those at present used.

According to this invention, a washing plunger, dolly or the like comprises side members suitably spaced at their lower ends 20 or edges and connected together by or fitted with rods, bars or the like forming a cage-like structure. The side members are preferably inclined towards each other, and taper upwardly so that their upper ends or 25 edges lie close to or in contact with each other and the connecting rods, bars or the like may be arranged at or near their front and rear and/or lower edges.

In the accompanying drawings, Fig. 1 is 30 a perspective view and Fig. 2 a transverse section of one construction of plunger, dolly or the like in accordance with the invention. Fig. 3 is a longitudinal section, and Fig. 4 a 35 plan illustrating a modified means of securing the handle of the plunger, dolly or the like.

Referring to the drawings, the side members *a* consist of two pieces of wood inclined upwardly towards each other in the form 40 of an inverted letter V and preferably with the grain of the wood running lengthwise between their upper and lower ends. The side members are of greater width at their lower ends *b* than at their upper ends *c* so 45 that they taper from the former to the latter. The side members preferably also taper in thickness from their lower ends *b* to their upper ends *c*, and are rounded off or beveled at their edges or corners as indicated 50 at *d*, to avoid sharp edges or corners liable to splinter or become rough and to tear or otherwise damage the clothes or articles operated upon.

The side members *a* are connected by 55 horizontal bars *f* preferably of wood and circular section, and arranged near the

front and rear and lower edges of the members. The ends of the bars *f* are fitted in recesses or holes *m* formed in the side members and which may extend only partially or completely therethrough. The bars *f* serve to secure the side members *a* together and the ends of the bars may be secured in the recesses or holes *m* simply by being driven therein or by means of dowels or pins *n*, as 60 indicated in Fig. 2. The side members *a* may be further secured together by one or more bars *g* arranged between the front and rear bars *f* and about the middle of the width of the side members. The ends of the 65 bar or bars *g* may be inserted or driven into recesses or holes *o* in the side members *a* and, if desired, secured therein by dowels or pins *p*, as also indicated in Fig. 2. The side members *a* are also formed with a plurality of 70 holes *e* or other apertures through which in use the water in which the clothes or articles are cleansed may pass.

The plunger or dolly is provided with an operating handle *h* secured to its upper end. 75 The end of the handle *h* may be fitted in a hole or recess formed between the upper ends of the side members *a* and be secured therein by a dowel pin, nail or the like *j*, as shown in Figs. 1 and 2. Alternatively, an 80 apertured cap or disc *k* may be secured on the upper end of the side members *a* and the end of the handle fitted in the aperture of the cap or disc and secured therein by a 85 dowel, pin, nail or the like *j*, as shown in Figs. 3 and 4. In the latter arrangement, the cap or disc *k* also assists in holding the 90 side members together.

A washing plunger, dolly or the like constructed as above described considerably reduces splashing of the water in comparison with known plungers, dollies or the like, the water which spurts and splashes within the device being broken up by the bars *f*. Owing to the shape and arrangement of the side 95 members lapping or clinging of the clothes or articles on or to the plunger, dolly or the like is reduced to a minimum and the construction of the plunger, dolly or the like is such that it will withstand rough usage. 100

What I claim as my invention and desire to secure by Letters Patent is:—

1. A washing plunger, dolly or the like, comprising side members suitably spaced at their lower ends and connected together by 110 bars.
2. A washing plunger, dolly or the like

according to the preceding claim, wherein the side members are inclined towards each other upwardly, and the bars are arranged near the edges of the side members.

3. A washing plunger, dolly or the like, according to claim 1, wherein the side members are connected together by a bar arranged at about the middle of their width.

4. A washing plunger, dolly or the like, according to claim 1, wherein the side members taper in width from their lower to their upper ends.

5. A washing plunger, dolly or the like, according to claim 1, wherein apertures are provided in the side members.

6. A washing plunger, dolly or the like, comprising a handle, a pair of divergent strips connected together and to the handle at their upper ends, and bars connecting said strips along their side edges and divergent end edges.

7. A washing plunger, dolly or the like, comprising a pair of divergent strips and bars connecting said strips along their side edges and divergent end edges.

8. A washing plunger, dolly or the like, comprising a pair of divergent strips, a handle connected to said strips at their convergent ends, and spaced bars connecting the divergent end edges of said strips.

9. The plunger, dolly or the like, as set forth in claim 8 in which the strips are perforated from face to face.

10. The plunger, dolly or the like, as set forth in claim 7 in which the strips are 35 perforated from face to face.

11. A washing plunger, dolly or the like, comprising divergent strips, a cap member connecting said strips at their convergent ends, a handle connected to said cap member, and spaced bars connecting the divergent portions of the strips. 40

12. A washing plunger, dolly or the like, comprising divergent strips, a cap member connecting said strips at their convergent ends, a handle, a pin passing through the handle and cap member to anchor the handle to said member, and spaced bars connecting the divergent portions of the strips. 45

13. A washing plunger, dolly or the like, comprising a pair of divergent strips, an apertured cap member connecting said strips at their convergent ends, a handle passing through and anchored to said cap member, and spaced bars connecting the divergent portions of the strips. 50 55

In witness whereof I have hereunto set my hand.

ABRAHAM TAYLOR.
